Design U.S. Appl. No. 29/544,172 for Bottle, filed Oct. 30, 2015.

Primary Examiner — Dana Meyrow

(74) Attorney, Agent, or Firm — Fross Zelnick Lehrman & Sissu, P.C.; Charles T. J. Weigell, Esq.

(57) **CLAIM**

The ornamental design for bottle, as shown and described.

DESCRIPTION

FIG. 1 is a front perspective view of a bottle showing my new design;

FIG. 2 is a front view thereof;

FIG. 3 is a back view thereof;

FIG. 4 is a side view thereof;

FIG. 5 is the other side view thereof;

FIG. 6 is a top view thereof; and,

FIG. 7 is a bottom view thereof.

The thicknesses of the bottle walls are not substantial and form no part of the claim.

The stippling indicates a contrasting opaque surface.

The broken line showing of the bottom portion of the bottle shows unclaimed subject matter for the design in those drawings.
